US00D931305S

(12) **United States Design Patent** (10) Patent No.: **US D931,305 S**
 Varghese et al. (45) Date of Patent: **** Sep. 21, 2021**

(54) **DISPLAY PANEL OR PORTION THEREOF WITH A GRAPHICAL USER INTERFACE**

(71) Applicant: **Nutanix, Inc.**, San Jose, CA (US)

(72) Inventors: **Jibin Varghese**, Udaipur (IN); **Chhavi Gopal Shrivastava**, Bhopal (IN); **Atreyee Maiti**, Pune (IN); **Shyama Sundar Durisetti**, Pleasanton, CA (US); **Himanshu Shukla**, San Jose, CA (US)

(73) Assignee: **Nutanix, Inc.**, San Jose, CA (US)

(**) Term: **15 Years**

(21) Appl. No.: **29/719,125**

(22) Filed: **Dec. 31, 2019**

(51) LOC (13) Cl. **14-04**

(52) U.S. Cl.

USPC **D14/485**

(57) **CLAIM**

The ornamental design for a display panel or portion thereof with a graphical user interface, as shown and described.

DESCRIPTION

The sole FIGURE is a front view of a display panel or portion thereof with a graphical user interface showing our design.

The outermost broken line illustrates a display panel or portion thereof that forms no part of the claimed design. The remaining broken lines, including all text, illustrate portions of a graphical user interface and form no part of the claimed design.

1 Claim, 1 Drawing Sheet
